US00D892427S

(12) **United States Design Patent** (10) **Patent No.:** **US D892,427 S**
(45) **Date of Patent:** **** Aug. 11, 2020**

(54) **PET TREAT**

(71) Applicant: **BIG HEART PET, INC.**, Orrville, OH (US)

(72) Inventors: **Walker Cavalcanti**, Hudson, OH (US); **Yu-Hui Lee**, Copley, OH (US); **Raul Subia**, Fullerton, CA (US)

(73) Assignee: **BIG HEART PET, INC.**, Orrville, OH (US)

(**) Term: **15 Years**

(21) Appl. No.: **29/694,680**

(22) Filed: **Jun. 12, 2019**

Related U.S. Application Data

(62) Division of application No. 29/612,049, filed on Jul. 27, 2017.

(51) **LOC (12) Cl.** **01-01**

(52) **U.S. Cl.**

USPC **D1/125**

(58) **Field of Classification Search**

USPC D1/100–130, 199; 426/5, 76, 87, 92, 94, 426/95, 99, 101, 103, 104, 108, 134, 426/138–139, 143, 144, 279, 282, 283, 426/391, 514, 549, 559, 560, 660, 808; D9/439, 669; D24/130; D6/597, 598, D6/601; D21/488–490, 493, 680; D23/366, 386, 415; 239/44; D8/83

(57) **CLAIM**

The ornamental design of a pet treat, as shown and described.

DESCRIPTION

FIG. 1 is a font, left, top perspective view of a pet treat.

FIG. 2 is a bottom plan view thereof;

FIG. 3 is a top plan view thereof;

FIG. 4 is a left side elevation view thereof;

FIG. 5 is a right side elevation view thereof;

FIG. 6 is a front elevation view thereof; and,

FIG. 7 is a rear elevation view thereof.

The shade lines shown in the figures illustrate contour, and not texture, color, shading, or surface ornamentation.

The broken lines shown in the figures depict portions of the pet treat that form no part of the claimed design.

1 Claim, 5 Drawing Sheets
